UNITED STATES PATENT OFFICE.

HAROLD CEDERBLAD, OF SAN FRANCISCO, CALIFORNIA.

TOY.

1,378,765.

Specification of Letters Patent. Patented May 17, 1921.

Application filed October 5, 1920. Serial No. 414,822.

To all whom it may concern:

Be it known that I, HAROLD CEDERBLAD, a citizen of the United States, residing at San Francisco, in the county of San Francisco and State of California, have invented new and useful Improvements in Toys, of which the following is a specification.

This invention relates to a toy and has particular reference to a round-about toy 10 designed for the entertaining and amusement of children.

One object of this invention is to provide a toy which comprises a circular track about which a toy figure is adapted to travel, being 15 actuated by the application of power furnished from a winding mechanism.

Another object of this invention is to provide a toy of the character described which is simple in construction, attractive in appearance, inexpensive in manufacture, and a 20 toy which can be knocked down and then marketed in such condition and then set up for use by the purchaser.

Other objects and advantages of the invention will be apparent during the course 25 of the following description.

In the accompanying drawings forming a part of this specification and in which like numerals are employed to designate like 30 parts throughout the same,

Figure 1 is a top plan view of my improved toy,

Fig. 2 is an end elevation of the same,

Fig. 3 is a side view partly in section 35 showing the winding mechanism forming a part of my invention,

Fig. 4 is a detail of one of the wheels and its associated parts, and

Fig. 5 is a sectional view of a clamping 40 element forming part of my invention.

In the drawings wherein for the purpose of illustration is shown a preferred embodiment of my invention, the circular track consists of sections 6 and 7 which are held 45 in fixed relation, as shown to advantage in Figs. 1 and 3, by a clamping element 8 substantially U shaped in cross section. Connecting the sides of the track there are provided cross timbers 9 which enter grooves 10 formed in the clamping element, while the bars 12 which connect the opposite ends 50 of each section of the track are received in grooves 13 of the clamping element 8. Fixed in the recess 14 in the top of the 55 clamping element is one extremity of a bearing 15 which serves as a pivot point for a

top board 16. This board has depending beneath the same a support 17 which is provided with a horizontal bore 18. The support can either be made integral with the 60 top board 16 or detachably fastened thereto, and has formed in its free end a recess 19 which receives the other extremity of the bearing pin 15.

Extending beneath and adjacent the respective ends of the top board 16 there is provided an arm 20 and likewise a pair of bifurcated recessed arms 21, while also disposed beneath the top board 16 is an extension 22. The arm 20 has integrally formed 70 therewith a hollow bearing 23.

Vertically positioned within the bifurcated arms 21 is a wheel or roller 24, which encircles a pedaling element 25. Washers 26 serve to hold the wheel in a fixed position 75 and prevent contact of the wheel with the arms 21.

The numeral 27 designates a second wheel which is provided with a crank arm 28 for the purpose of rotating the same. Penetrating 80 the hollow bearing 23 and the wheel 27 is a small shaft 29 provided with an eye 30, while connecting the eye 30 of the pin 29 and the extension of the top board is an elastic element 31. This elastic element is 85 adapted to be passed through the horizontal bore 18 and by a winding and unwinding operation serves to impart rotary movement to the wheels to cause the same to travel over the circular track. 90

Formed integral with the top board 16 is a yoke 32 provided with a seat portion 32' which serves to support a toy figure 33 of any desired type. The feet of the toy figure are adapted to rest in the pedal element in 95 order to imitate a person in the act of pedaling, and the desired result will be obtained when the wheels start to revolve. It will be apparent to those skilled in the art that the wheel 27 of the device will only begin to 100 rotate when the elastic element is released after being wound as tightly as possible, which winding action is accomplished by the fingers of the operator grasping the crank provided on the wheel 27. 105

For packing and shipping, the various parts are easily disassembled, and the device can be readily set up by inserting the clamp over the sectional bars and then completing the construction of the toy, as shown to advantage in Fig. 1. 110

It is to be understood that the form of my

invention herewith shown and described, is to be taken as a preferred example of the same, and that various changes in the shape, size and arrangement of parts may be resorted to without departing from the spirit of the invention or the scope of the subjoined claim.

Having thus described my invention, I claim:—

- 10 In a toy, the combination with a sectional circular track and a cross timber connecting the sections of said track, of a grooved U shaped clamping element adapted to hold the sections of said track in fixed relation, a 15 top board having an integral recessed sup-

port formed thereon, a bearing disposed between said support and said clamping element, wheels connected to and depending beneath said board, a pedaling element penetrating one of said wheels, a figure associated with said board and having a portion thereof connected with said pedaling element, means attached to said top board for supporting said figure, and winding mechanism for imparting rotary movement to said 25 wheels to cause the same to travel over the circular track.

In testimony whereof I affix my signature.

HAROLD CEDERBLAD.
